COMBINED MERCHANTISE DISPLAY STAND AND ADVERTISING PLACARD SUPPORT

Steve Iannucci, Caldwell, N.J., assignor to Gabriel Frank Associates, Inc., Englewood Cliffs, N.J., a corporation of New Jersey

Filed Dec. 9, 1960, Ser. No. 63,177

Term of patent 14 years

(Cl. D80—9)

Fig. 1.

Fig. 2.

Fig. 3.

*Fig.4.Fig.5.*FIGURE 1 is a front, perspective view of a combined merchandise display stand and advertising placard support embodying my new design.

The advertising placard represented by broken lines in the several views is for purposes of illustration only.

I claim:

The ornamental design for a combined merchandise display stand and advertising placard support, substantially as shown and described.
